UNITED STATES PATENT OFFICE

ALBERT KEUP, OF GELSENKIRCHEN, GERMANY

APPARATUS FOR CASTING HOLLOW BODIES IN CHILL MOLDS ROTATABLE ABOUT VERTICAL AXES

Application filed July 17, 1931, Serial No. 551,497, and in Germany December 10, 1930.

This invention is for a method and apparatus for casting hollow bodies in chill molds rotatable about vertical axes.

In the production of hollow bodies by casting in chill molds rotating about vertical axes, it is usual to pour the molten metal into the mold so that it falls onto the bottom thereof and thereafter rises up the walls due to centrifugal action as the mold rotates. This method produces various faults in the hollow bodies so cast, particularly when the same are of relatively large diameter and great height. These faults are produced by the stream of molten metal, as it is poured into the mold, striking the bottom thereof and splashing upwardly on to the walls, resulting in the production of scales and flakes on the outer surface of the hollow body which, in many instances, makes an extensive subsequent treatment necessary before the body can be rolled or forged. Moreover, by the method described, the bottom of the chill mold is subjected to relatively heavy wear by the falling of the molten metal thereon.

This invention comprise a method of casting hollow bodies in a chill mold rotating about a vertical axis which consists in introducing molten metal into the base of the rotating mold where the flow of metal into the upper part of the mold is controlled in such a manner that the metal moves into contact with the walls of the mold solely as an annular mass rising from the bottom of the mold.

In a suitable apparatus for carrying the method according to the invention into effect, the base of a chill mold is constructed in the form of a plate provided with a central recess arranged to receive metal poured into the mold, and prevent it from being splashed up on to the walls of the mold, the plate being constructed so as to distribute the metal from the recess in an upward direction adjacent to the inner walls of the mold.

In order that the invention may be fully understood, reference is directed to the accompanying drawing in which:—

Figure 1 is a vertical section of a chill mold constructed for carrying the method according to the invention into effect, and

Figure 2 illustrates in plan the base plate of the mold shown in Figure 1.

Referring to the drawing, the chill mold is provided with an interchangeable base plate *a* in the center of which a recess is formed arranged to receive a member *b* formed of refractory material. The member *b* has a recess formed therein which communicates at its lower end with a series of radially disposed channels as illustrated in Figure 1. The recess in the member *b* is of a configuration such as that illustrated in Figure 1 which ensures that molten metal poured thereinto is not splashed upwards on to the walls of the mold. A downward depression is provided in the member *b* opposite to the lower open end of the recess therein where the same communicates with the radially disposed channels.

A radially disposed refractory member *c* is located in a recess in the upper surface of the plate *a* adjacent to each of the radially disposed channels in the member *b* and is provided with a conduit arranged in communication with the said channel. The conduit is directed upwardly so as to open into the mold adjacent to the inner wall thereof.

The chill mold above described is employed as follows:—

Molten metal is poured into the mold as it rotates so as to fall within the recess in the member *b* from whence it flows through the radially disposed channels in the said member and through the conduits in the members *c* and thence upwardly into the mold so as to effect the casting of a hollow body therein. It will be appreciated that the centrifugal action developed during the rotation of the mold causes all the molten

metal introduced into the recess in the member *b* to be carried through the radial channels therein and thence through the conduits in the members *c* into the mold, and the speed of rotation of the mold may be regulated as desired so as to produce the desired flow of the metal into the mold. Progressive stages of the flow of the molten metal upwardly into the chill mold are indicated

10 in dotted lines in Figure 1.

The flow of the metal through the conduits into the mold is effected uniformly and smoothly without causing the metal to be splashed on to the walls of the mold and the 15 hollow body produced is thus free from the scales and flakes on the outer surface which are produced by known methods. The casting is thus in condition to be rolled or forged without any supplementary preparation.

20 The refractory nature of the members *b* and *c* prevents the blocking of the channels in the conduits therein by solidified metal and it will be appreciated that if the members *b* and *c* become worn they may be readily replaced.

I claim:

1. A casting mold for casting hollow bodies by vertical centrifugal casting comprising a replaceable bottom having a recessed central block provided with a plurality of channels leading from said recess and a plurality of channel blocks arranged about said central block and having passageways therein communicating with the 35 channels of said central block to conduct metal from the recess of said central block into the mold.

2. A casting mold according to claim 1 having a recessed central block the upper 40 portion of which recess is shaped to fit the inwardly flowing casting jet.

In testimony whereof I have signed my name to this specification.

ALBERT KEUP.
